ELECTRON DISCHARGE DEVICE

Richard Orthuber, Berlin, and Eberhard Steudel, Berlin-Dahlem, Germany, assignors to Allgemeine Elektricitäts-Gesellschaft, Friedrich-Karl-Ufer

Application March 26, 1937, Serial No. 133,140
In Germany March 31, 1936

8 Claims. (Cl. 250—27.5)

It is known that two photo-electric currents can be amplified by an electron multiplier in the following manner: The photo-cathode forms one plate of a plate condenser, the other plate of which is provided with a layer capable of producing secondary electrons when bombarded by sufficiently high velocity electrons. To the plates of the condenser is applied an alternating voltage so that the electrons liberated at the photo-cathode are accelerated between the plates. At every impingement upon one of the two plates of the condenser or multiplier, secondary electrons are liberated which are thus multiplied or increased in number in this cascade-like manner. The thus-amplified photo-current can then be collected by means of a cylindrical anode provided between the electrodes or plates. An essential feature in the arrangement resides in the provision of a magnetic field, the direction of which is the same as the direction of the alternating electrostatic field.

The employment of this particular method of dynamic electron multiplication necessitates a comparatively complicated structure and system. The present improved photo-tube and amplifier does not suffer from these drawbacks, but is, as regards its structure and its operation, similar to an ordinary photo-tube as will appear from the detailed description forming part of this specification.

The essential features of this improved photo-tube and electron multiplier are that the photo-cathodes, the collector anode, the tuning system, and the oscillation generator are housed in a common vacuum vessel.

Such a compact arrangement of the elements and electrodes mentioned is rendered possible first of all by making use of a frequency of the order or magnitude of 1000 megacycles per second, whereby the possibility is afforded to give the alternating voltage a comparatively large amplitude. The effects obtained by the large amplitude are first, a greater output of secondary electrons and secondly, because of the high frequency of the alternating voltage and the effect of the larger amplitude, the electrons need cover only a short distance within a half-cycle whereby it is possible that the distance between the plates of multiplier electrodes can be small. Another advantage of the employment of the high frequency, that is to say, of short waves, is that the tuning can be effected by a short Lecher system provided in the same vacuum vessel.

The invention may best be described by referring to the drawings, wherein:

Figure 1 represents one form of a multiplier constructed in accordance with the present invention;

Figures 2 and 3 represent modifications of the form shown in Figure 1, and

Figures 4 and 5 represent other forms of photo-electron multipliers.

Referring now to Figure 1, an oscillation generator 1 is coupled with the Lecher wires 3 and 4 by means of the condensers 2. (This oscillation generator is shown only in Figure 1 and is omitted in Figures 2 and 3, and must be supposed to be situated near the right-hand end of each of these figures within the vacuum tube.) The oscillator may be, for instance, a Barkhausen short-wave oscillator or may have any other wiring connections suited for the production of high frequency oscillations. If a particularly great constancy of the amplification is desired, it may be necessary to stabilize the oscillator frequency.

In Figure 1 the photo-cathode electrode 5 must be designed as a semi-transparent layer so that the light arriving in the direction 7 from the window 8 can find access into the multiplier. Electrodes 5 and 6 are the plates of the multiplier and the secondary electrons produced at the plates are collected by the anode 9. For focusing the electrons a magnetic field is produced in the coil 10 which is positioned outside the tube.

In the arrangement shown in Figure 2, the magnetic field is produced by a magnet 11, which, if desired, may be a permanent magnet. The pole piece of the magnet is provided with an aperture 12 to permit the passage of light on to the photo-cathode electrode 13. The electrodes 13 and 14 form the plates of the multiplier and electrode 14 is either semi-transparent or is provided with an aperture 15 in order to permit light to reach the electrode 13.

In Figure 3 a more compact arrangement of the members concerned is attained by including the magnet poles 11 within the tube. The pole pieces at the same time, serve as carriers for the photo-cathodes or electrodes 13 and 14.

In Figures 4 and 5 the electron multiplier is used as the oscillation generator. In Figure 4 elements 16 and 17 denote the two cathodes or electrodes of the multiplier across which is connected a condenser 18 and a self-inductance 19. The anode cylinder 20 can be connected, for instance, with the middle portion of the self-inductance 19, and a source of potential may be included in this connection. In this wiring connection the multiplier excites itself, if the ac-

celerating circuit with the capacity 18 and the self-inductance 19, and the multiplier capacity are tuned to the natural oscillation period of the multiplier. A certain illumination is required, however, in order to initiate the operation of the device.

The alternating voltage arising at the self-inductance 19 may now be used to actuate a second multiplier, provided for the amplifying of photo-electrons liberated from one of these electrodes. Such an arrangement, which constitutes a photo-tube and an amplifier, is illustrated in Figure 5. The multiplier 22 serves in this case for the generation of oscillations and the multiplier 23 serves for the amplification. Both multipliers are connected together by means of the mutual inductances 24 and 25, which presents the advantages that the light arriving in the direction 26 can be used at the same time for the excitation of the oscillation generator 22, in that it is distributed to both multipliers by means of a suitable mirror 27, the light being transmitted through passages 28.

With those constructional forms in which permanent magnets are arranged within the tube, these magnets can, if desired, be designed as part of the Lecher system.

Various modifications may be made in the invention without departing from the spirit and scope thereof, and it is desired that any and all such modifications shall be considered within the purview of the invention, except as limited by the hereinafter appended claims.

We claim:

35 1. An electron discharge device comprising an envelope, a source of oscillations within the envelope of the Barkhausen type comprising an electron emitter, a grid element and an anode, a Lecher-system comprising a pair of conductors, means coupling the conductors to said grid and anode, a pair of electron emissive surfaces in the envelope one of which is light responsive, means connecting said surfaces to said conductors, a collector anode adjacent said surfaces, and means to produce a magnetic field in the region of said surfaces.

2. An electron discharge device comprising an envelope, means in the envelope adapted to produce oscillations comprising an electron emitter, a grid electrode and an anode, a Lecher tuning system comprising a pair of parallel conductors, means coupling said conductors to said grid and anode, a pair of surfaces having high secondary electron emission qualities in the envelope, one of said surfaces being light responsive, means positioning said surfaces in substantially parallel relation and connecting said surfaces to said conductors, a collector anode for said surfaces, and means to produce a magnetic field substantially normal to said surfaces.

3. An electron discharge device comprising an envelope, means in the envelope adapted to produce oscillations comprising an electron emitter, a grid electrode and an anode, a tuning system comprising a pair of parallel conductors, means coupling said conductors to said grid and anode, a pair of surfaces having high secondary electron emission qualities in the envelope, means positioning said surfaces in substantially parallel relation and connecting said surfaces to said conductors, a collector anode for said surfaces, and

means to produce a magnetic field substantially normal to said surfaces, said last named means being located within the envelope.

4. An electron discharge device comprising an envelope, means in the envelope to produce oscillations comprising an electron emitter, a grid electrode and an anode, a tuning system comprising a pair of parallel conductors, means coupling said conductors to said grid and anode, a pair of surfaces having high secondary electron emission qualities in the envelope, means positioning said surfaces in substantially parallel relation and connecting said surfaces to said conductors, a collector anode for said surfaces and means to produce a magnetic field substantially normal to said surfaces, said last named means being located within the envelope and forming at least a part of the tuning system.

5. An electron discharge device comprising an envelope, means within the envelope to produce oscillations, a pair of parallel conductors in the envelope forming a Lecher tuning system, means connecting said conductors to the source of oscillations, a pair of surfaces having a secondary electron emission ratio greater than one, one of said surfaces being light responsive, a collector anode for said surfaces, means positioning said surfaces in substantially parallel relation and connecting said surfaces to said conductors, and means to produce a magnetic field substantially normal to said surfaces.

6. An electron discharge device comprising an envelope, means within the envelope to produce oscillations, a pair of parallel conductors in the envelope forming a tuning system, means connecting said conductors to the source of oscillations, a pair of surfaces having a secondary electron emission ratio greater than one, a collector anode for said surfaces, means positioning said surfaces in substantially parallel relation and connecting said surfaces to said conductors, and means to produce a magnetic field substantially normal to said surfaces, said last named means including magnetic pole pieces one of which is provided with an opening extending in the direction of one of the surfaces.

7. An electron discharge device comprising an envelope, means in the envelope to produce oscillations, a pair of magnetic members in the envelope, means connecting said members to the source of oscillations and positioning the pole faces of the member in substantially parallel relationship, means on each pole face for producing secondary electrons under electron bombardment, one of said means being light responsive, and a collector anode for said means.

8. An electron discharge device comprising an envelope, means in the envelope to produce oscillations, a pair of parallel magnetic members in the envelope, means connecting said members to the source of oscillations and positioning the pole faces of the member in substantially parallel relationship, means on each pole face for producing secondary electrons under electron bombardment, and a collector anode for said means, one of said last named means being light responsive and one of said pole faces being provided with an opening extending in the direction of the other pole face.
